UNITED STATES PATENT OFFICE.

JOHN V. W. VANDENBURGH, OF CHICAGO, ILLINOIS.

DESIGN FOR A PENDANT.

SPECIFICATION forming part of Design No. 21,152, dated November 3, 1891.

Application filed October 10, 1891. Serial No. 408,366. Term of patent 3½ years.

To all whom it may concern:

Be it known that I, JOHN V. W. VANDENBURGH, a citizen of the United States, residing at Chicago, in the county of Cook and State 5 of Illinois, have invented and produced a new and original Design for Pendants, of which the following is a specification, reference being had to the accompanying drawings, forming a part hereof, in which—

10 Figure 1 is a view of the pendant or charm as suspended from a chain. Fig. 2 is a view in elevation of the pendant or charm.

In the drawings, A represents the longitudinally-oval-shaped body of the pendant, having its sides and one end on curved lines to 15 present from all points in elevation a raised oval-shaped face, and having the apex or small end of the body cut by a face in cross plane to form an edge around the apex end, 20 with fine zigzag lines a running therefrom over the face of the apex end, producing, when viewed in elevation, the outline of an egg having an apex end struck to be flat-crushed.

B is an eye or loop.

The essential feature of my design is the pendant having the representation in outline of an egg viewed in elevation with its apex end crushed flat for the egg to stand upright, and having its globous surface curved peripherally and cut at its apex or smaller end by a face in cross plane for a flattened end, and having zigzag lines radiating from the peripheral edge of said flattened end.

25 What I claim as new, and desire to secure 35 by Letters Patent, is—

The design for a pendant or charm, substantially as herein shown and set forth.

JOHN V. W. VANDENBURGH.
